UNITED STATES PATENT OFFICE.

CHARLES E. ONGLEY, OF YONKERS, NEW YORK.

WATCHMAN'S ELECTRIC TIME-RECORDER.

SPECIFICATION forming part of Letters Patent No. 443,787, dated December 30, 1890.

Application filed January 20, 1890. Serial No. 337,424. (No model.)

To all whom it may concern:

Be it known that I, CHARLES E. ONGLEY, a citizen of the United States, residing at Yonkers, in the county of Westchester and State 5 of New York, have invented a certain new and useful Improvement in Watchmen's Time-Recorders, of which the following is a specification.

My invention relates to watchmen's time- 10 recorders operated by individual electrical signal-transmitters, and provided with time-printing type-wheels, which print upon a record-strip the time when signals are sent in, the number of the transmitter-box from which the signal is sent being indicated by the number of times that the hour is printed on the strip.

The main object of my present invention 15 is such an improvement upon the apparatus of his general character that less space will be consumed on the record-strip than is required in the earlier apparatus, in which the printing of the hour has sometimes to be repeated a great many times in recording one signal, whereby a large amount of paper is consumed in a short time. Further, my object is generally to provide a simple and efficient construction for a time-recorder and for 20 signal-transmitters used in connection therewith, and simple and effective electrical connections between the recorder and the transmitters.

The main feature of my invention consists 25 in providing the recorder, which prints upon a strip, as before, with time-printing type-wheels controlled by a clock-movement, and other type-wheels for printing the number of the box, which are electrically controlled from the transmitter, the recorder being also provided with printing mechanism controlled 30 from the transmitter independently of the number type-wheels, for causing the impressions of the type-wheels on the strip, so that when such impression is made the number of the box and the time of the signal will be 35 simultaneously impressed on the paper. The transmitter used preferably with such a recorder is a modification of the common individual signal-transmitter, and is provided 40 with contacts controlling the operation of the number-printing type-wheels of the register,

and also with a contact controlling the printing mechanism of the recorder, the latter contact being made after the former, so that in the operation of the transmitter the number-printing wheels of the recorder are first set 55 at the right number, and then the printing is accomplished, the time-printing type-wheels being constantly set at the right position by the clock-movement.

My invention further consists in the various novel devices and combinations of devices employed by me in fully accomplishing the above-named objects, as hereinafter set forth and claimed.

My invention is illustrated in the accompanying drawings.

Figure 1 is a front view of the transmitter with the outer cover removed. Fig. 2 is a side elevation of the same with the side of 70 the box removed; Fig. 3, a top view of the break-wheels and contact-springs of the transmitter; Fig. 4, a front elevation of the working parts of the recorder, the clock-dial and portions of the clock-movement being omitted; Fig. 5, a top view of the same; Fig. 6, a horizontal section on the line 6 6 of Fig. 4; Fig. 7, a central horizontal section through the type-wheels, and Fig. 8 a diagram of the circuits connecting a transmitter with the recorder.

I will first describe the construction and operation of the transmitter.

A is a suitable box.

B is a spring-motor put under tension by a 85 handle C outside of the box, as is usual in district call-boxes. Instead of, however, employing, as usual, one break-wheel turned by the spring-motor, I have two wheels a and a' on the same spindle and turning together. 90 Each of these wheels has on its periphery several projecting teeth which co-operate in transmitting a signal, and in the path of movement of such teeth are two contact-springs b and b', one for each wheel. The 95 teeth of one wheel are preferably placed in advance of the other, and it will be seen that as the break-wheels make a revolution two sets of electrical impulses will be transmitted, and each set will indicate one of the figures 100 composing the number of the box. The box shown having five teeth on the first wheel

and four on the second, the number transmitted will be "54." It is evident that both numbers might for some purposes be transmitted simultaneously—that is, when it is only desired to furnish a printed record of the number—but I place one set of contacts in advance of the other, in order that the signal may be also given upon a single-stroke bell included in the circuit, as will be hereinafter explained.

Upon a wheel *c* of the train of gearing within the transmitter is placed a pin *d*, in the path of movement of which is a contact-spring *e*. The pin *d* is so placed that it will engage the spring *e* after the teeth of both break-wheels have passed under their contact-springs. The contact-spring *e* is that which controls the printing mechanism of the recorder.

From the transmitter circuits extend as follows: The wire 1 is the main circuit from the battery and is connected with an uninsulated binding-post, so as to bring the metal box into circuit, as usual. A wire 2 extends from the contact-spring *b*, a wire 3 from the contact-spring *b'*, and a wire 4 from the contact-spring *e*, so that at one revolution of the wheel *c* the circuits will close in the following order: first, the circuit 2, then circuit 3, and, finally, circuit 4.

It is evident that I may provide the box shown with additional contact devices controlling circuits for operating fire and other apparatus. Since, however, the present application relates only to the operation of the recorder, I have omitted these additional devices from the drawings, so as to avoid unnecessary complication.

Referring now to the register or recorder shown in Figs. 4, 5, 6, and 7, it will be understood that the working parts shown are inclosed in a suitable case, and they are mounted on a base *D*, within which are the feeding devices for the record-strip, which I have not considered it necessary to fully illustrate. By such devices, which are controlled by the magnet *E*, which also controls the printing mechanism, the record-strip of paper tape *F* is fed from a roll *G* through the recorder passing under the four type-wheels *H* *H'* *I* *I'*, which are placed in line side by side. The two inner type-wheels *H* and *H'* are operated or controlled by a suitable clock-movement, most of the parts of which are not shown, and which is wound up when necessary. The type-wheel *H* prints the hours, and is revolved one space every sixty minutes, and the type-wheel *H'* prints the minutes, and is revolved one space every five minutes. The mechanism for revolving these wheels is as follows: *f* is a toothed wheel forming a part of the clock-train, with the teeth of which engages the pawl *g*, carried at the end of the jointed arm *h*, pivoted at *i*, and carrying at its upper end a weight *K*. Attached to the hour type-wheel *H* is a ratchet *k*, and attached to the minute-wheel *H'* is a ratchet *k'*. These ratchets are

engaged by a swinging dog *l*, whose end has two teeth, one longer than the other, as illustrated in Fig. 6. The dog *l* is hung from a pivoted arm *m*, on the top of which is a flat plate *n*; also suspended from the arm *m* is a lever *o*, having a tooth which engages another ratchet *k* outside the time-wheels, said lever being retracted by a spring *p*. It will be seen that as the toothed wheel *f* revolves, engaging with the pawl *g*, such wheel being on the arbor of the hour-hand of the clock and provided with twelve teeth, it will lift the weight *K* until the pawl *g* passes over a tooth, when the weight *K* will drop, the arm carrying the weight striking on the plate *n*, and will move the arm *m* and dog *l*, so that such dog will turn the time-wheel with which it is in engagement. The stop-lever *o* also immediately drops into the ratchet *k* and prevents any greater movement of the type-wheel than is necessary to advance it one space. The minute-wheel *H'* is thus advanced every five minutes, and at the twelfth movement the long tooth of the dog *l* enters an unusually-deep notch *r* in the ratchet *k'*, so that at this time the short tooth of the dog engages the ratchet of the hour-wheel and both the wheels are turned together, the hour-wheel being thus advanced one space. This arrangement, in which the weight is lifted by the clock-train and dropped positively to effect the movement of the type-wheels, is a very simple and effective one for the purpose, inasmuch as it furnishes a positive movement, and one which is instantaneous and not dependent upon the tension of springs.

The record-strip *F* passes below the type-wheels and between them and the printing-bed *s*, carried at the end of the lever *L*, which is connected with the armature-lever *L'*, controlled by the magnet *E*, so that when such magnet is energized it throws the printing-bed up against the tape and presses the same against the type-wheels, so that such characters as are lowermost on the type-wheels at the time are printed on the strip. *t* is an inking-ribbon for inking the type-wheels.

The arrangement shown for the inking-ribbon is a common one, and I do not consider it necessary to enter into a description of its details.

Supported above the apparatus upon suitable standards, as shown, are two electromagnets *M* and *M'*. Below the poles of each magnet is an armature-lever *N* or *N'*, provided with retracting-springs *u*, carrying at their outer ends the pivoted spring-retracted dogs *v* *v'*, which respectively operate the number-printing type-wheels *I* and *I'*. These pivoted dogs engage, respectively, at *v* with ratchets *O* and *O'*, connected with the type-wheels *I* and *I'*, and turn said type-wheels by a step-by-step movement, according as the armatures are lifted by the magnets *M* and *M'*, the retaining-pawls or spring-catches *w* dropping into the ratchets after each move-

ment and holding them from turning backward. Each type-wheel I I' is provided with a coiled spring P for returning it to its normal position when it is released. A catch x is provided for holding the dog and retaining-pawl out of engagement during the return movement of the type-wheel, this catch being tripped by a pin y on the wheel and prevented from excessive downward movement 10 by the stop-pin x' .

Now referring to the diagram, Fig. 8, it will be seen that the magnet E of the recorder is in circuit 4 from the contact-spring e of the transmitter. The magnet M is in the circuit 15 3 from the contact-spring b' , and magnet M' is in the circuit 2 from the contact-spring b . These are all multiple-arc circuits from the main battery Q . In the return-wire 5, which is common to both magnets M and M' , I prefer to place a single-stroke bell R , which may be situated in practice at any convenient point.

In operation the time-printing wheels II and II' are kept constantly at the right point to print the hour and minute by the clock-movement, and when a transmitter is operated the first effect is, as the contact-spring b engages the teeth on the wheel a' , that the magnet M' is energized five times and five successive impulses are communicated to the 20 armature-lever N' and pivoted dog v' , so that the type-wheel I' is moved five spaces and the figure "5" thereon is brought into the printing position, it being then held in this position by its catch w . Then in the transmitter, 25 the teeth on the break-wheel a engage the spring b' , and four impulses are communicated through the magnet M to the type-wheel I and the same is revolved, so as to bring the figure "4" into a printing position. 30 All the type-wheels being then in position, the spring e reaches the pin d in the transmitter and closes the circuit 4 through the magnet E , so that the printing-bed s is thrown up against the type-wheels and the number 35 45 of the box and the time of the signal are therefore printed on the tape in the manner shown in Fig. 5, the outer figures "5" and "4" indicating the number of the box and the inner figures showing that the signal was sent 50 in at 7.30 o'clock. The feeding mechanism for the tape feeds the tape on after this operation, this being, as usual, controlled by the magnet E .

It will be seen that the ends of the dogs v v' extend down close to the end of the lever L , which carries the printing-bed, and when the said lever is raised to print, said dogs are thrown back and are caught and held by the catches x , and in their movement they push 55 60 back the catches w , with pins on which they engage, and so release the type-wheels, which are immediately carried back by their springs to their original position, at which point the projecting ends of the catches x are met by 65 the pins y on the wheels, and these trip the catches and permit the dogs v and catches w to return to operating position.

It will be seen that as all the figures are in line across the strip very little space is consumed in printing each signal, and a large 70 saving in paper and also in ink is obtained, and the necessity of constantly renewing the paper roll is avoided. By the present arrangement, also, the record is made more easy to read, and less time is consumed in copying 75 it into record-books.

It will of course be understood that a suitable number of signal-transmitters—such as described and arranged for different numbers—are connected with the main circuit in 80 the ordinary manner. It is evident that in case the number of the box is composed of only one figure the transmitter may be provided with a single break-wheel and the recorder with a single number-printing type-wheel and operating mechanism therefor; but by connecting only one side of the register shown in circuit, so that only one type-wheel is operated, the same result is obtained. 90

What I claim is—

1. In a watchman's time-recorder, the combination of time-printing type-wheels controlled by a clock-movement, printing mechanism, an electro-magnet controlling said 95 printing mechanism, a number-printing type-wheel, and an independent electro-magnet controlling the same, substantially as set forth.

2. In a watchman's time-recorder, the combination of time-printing type-wheels controlled by a clock-movement, number-printing type-wheels, and electro-magnets independently controlling said number-printing type-wheels, respectively, substantially as set 100 105 forth.

3. In a watchman's time-recorder, the combination of four type-wheels arranged in line, two for printing hours and minutes and two for printing numbers, a clock-movement controlling the time-printing type-wheels, and electro-magnets independently controlling the number-printing type-wheels, respectively, substantially as set 110 115 forth.

4. The combination of a type-wheel, an electro-magnet for turning the same by a step-by-step movement, a stop for holding said type-wheel, a spring for returning the type-wheel, and a magnet whose armature operates a printing-bed and also engages the stop of 120 said type-wheel to release the same, whereby the type-wheel is returned to zero after the operation of printing, substantially as set forth.

5. In a watchman's time-recorder, the combination of time-printing type-wheels controlled by a clock-movement, a number-printing type-wheel, an electro-magnet for turning the same by a step-by-step movement, a stop for holding said type-wheel, a spring for returning the type-wheel, and a magnet whose armature operates a printing-bed and also engages the stop of said type-wheel to release 125 130 the same, whereby the type-wheel is returned

to zero after the operation of printing, substantially as set forth.

6. The combination of a type-wheel provided with a ratchet and dog engaging with the ratchet, a clock-movement, and a weight raised and dropped at intervals by the clock-movement and engaging said dog in its descent to turn the type-wheel, substantially as set forth. 65

7. The combination of a type-wheel provided with a ratchet and dog engaging with the ratchet, a clock-movement, a pawl engaging with a toothed wheel of said clock-movement, an arm connected with said pawl, and a weight carried by said arm and raised and lowered by the movement of said wheel and engaging said dog in its descent to turn the type-wheel, substantially as set forth. 70

8. The combination of a watchman's time-recorder having time-printing type-wheels controlled by a clock-movement, printing mechanism, an electro-magnet controlling said printing mechanism, a number-printing type-wheel, and an independent electro-magnet controlling the same, with a signal-transmitter affecting successively the circuits of the type-wheel magnet and the printing-magnet, substantially as set forth. 75

9. The combination of a watchman's time-recorder having time-printing type-wheels controlled by a clock-movement, number-printing type-wheels, and electro-magnets independently controlling said number-printing type-wheels, respectively, with a signal-transmitter affecting the circuits of said number-printing type-wheels, substantially as set forth. 80

10. The combination of a watchman's time-recorder having time-printing type-wheels controlled by a clock-movement, number-printing type-wheels, and electro-magnets independently controlling said number-printing type-wheels, respectively, with a signal-transmitter successively affecting the circuits of said number-printing type-wheels, substantially as set forth. 85

11. The combination of a watchman's time-recorder having time-printing type-wheels controlled by a clock-movement, printing mechanism, and electro-magnet controlling said printing mechanism, number-printing type-wheels, an electro-magnets controlling said number-printing wheels successively, with a signal-transmitter affecting successively the circuits of the type-wheel magnets and the printing-magnet, substantially as set forth. 90

12. In an electric signal-transmitter, the combination of two break-wheels, each having a number of contact-points co-operating

to transmit a signal, a contact-spring for each break-wheel, an additional contact-point turning with the break-wheels, and a contact-spring in the path of said additional contact-point, substantially as set forth. 95

13. In an electric signal-transmitter, the combination of the two break-wheels, each having a number of contact-points co-operating to transmit a signal, said break-wheels revolving together and one having its contact-points in advance of those of the other, and a contact-spring for each break-wheel, substantially as set forth. 100

14. The combination, with a time-recorder having time-printing type-wheels controlled by a clock-movement, of a number-printing type-wheel moved by an electro-magnet, printing mechanism controlled by another electro-magnet, a signal-transmitter having a break-wheel in the circuit of the magnet controlling the said number-printing wheel, and a circuit-closer in the circuit of the said printing-magnet, substantially as set forth. 105

15. The combination, with a time-recorder having time-printing wheels controlled by a clock-movement, a plurality of number-printing wheels controlled separately by electro-magnets, printing mechanism, and an electro-magnet controlling the printing mechanism, of a signal-transmitter having a break-wheel with contact-points in the circuit of each of the magnets controlling the number-wheels, and a circuit-closer in the circuit of the printing-magnet, substantially as set forth. 110

16. The combination, with the spring-retracted type-wheels, the magnet, and the dog carried by the magnet for turning the type-wheels, of the spring-catch for holding said type-wheels from backward movement, the printing-magnet, and the arm moved by the printing-magnet to trip said catch and release the type-wheel, substantially as set forth. 115

17. The combination, with a spring-retracted type-wheel, the magnet, and the dog moved by said magnet and engaging said type-wheel to move the same, of the spring-catch for holding the type-wheel from backward movement, the printing-magnet, the arm moved by the printing-magnet and arranged to drop said catch to release the type-wheel, the lock for holding said catch, and means actuated by the movement of the type-wheels for disengaging the lock from said catch, substantially as described. 120

This specification signed and witnessed this 115
10th day of January, 1890.

CHARLES E. ONGLEY.

Witnesses:

D. H. DRISCOLL,
W. PELZER.

It is hereby certified that Letters Patent No. 443,787, granted December 30, 1890, upon the application of Charles E. Ongley, of Yonkers, New York, for an improvement in "Watchmen's Electric Time-Recorders," were erroneously issued to said Ongley as sole owner of the said invention; that said Letters Patent should have been issued to said *Charles E. Ongley and Thomas W. Robertson, jointly*, each being owner of one-half interest, as shown by the record of assignments in this office; and that said Letters Patent should be read with this correction therein that the same may conform to the record of the case in the Patent Office.

Signed, countersigned, and sealed this 24th day of March, A. D. 1891.

[SEAL.]

CYRUS BUSSEY,
Assistant Secretary of the Interior.

Countersigned:

C. E. MITCHELL,
Commissioner of Patents.
